[57] CLAIM

The ornamental design for a wrist-borne device for use in therapy, as shown and described.

DESCRIPTION

FIG. 1 is a perspective view of a wrist-borne device showing my new design, the device being for use in therapy.

FIG. 2 is a top plan view thereof,

FIG. 3 is a bottom plan view thereof,

FIG. 4 is a view of one side thereof; and,

FIG. 5 is a view of the other side thereof.

The straps illustrated in broken lines in FIG. 1 do not form part of my claimed design.

The two opposite end elevations of the wrist-borne vibrating device are mirror images of one another.
